DRUM-SWITCH WITH MAXIMUM CUT-OUT.

1,155,978.

Specification of Letters Patent.

Patented Oct. 5, 1915.

Application filed December 8, 1914. Serial No. 876,125.

To all whom it may concern:

Be it known that I, MAX VOGELSANG, a subject of the German Emperor, and a resident of Frankfort-on-the-Main, Germany, have invented certain new and useful Improvements in Drum-Switches with Maximum Cut-Outs, of which the following is a specification.

My invention relates to improvements in drum switches with maximum cut-outs, and the object of the improvements is to provide a switch of this class which is simple in construction.

With this object in view my invention consists in connecting the regulating lever of the switch with the switch drum through a pawl and ratchet mechanism which is adapted to be thrown out of coupling position by means of a maximum relay. When the pawls are thus released, the switch drum which is connected with the regulating lever by a spring is thrown into zero position. Constructions of this kind are objectionable, because the operator must take up the pull of the spring which is connected at one end to the drum and at the opposite end to the regulating lever. Therefore in my improved apparatus locking means are provided which are controlled by the pawl and ratchet mechanism and lock the regulating lever in its positions, and the regulating lever is released at the end of the switching operation, so that it can be returned by the operator into zero position in which the pawls are again in engagement therewith. By the said return movement the spring is simultaneously put under tension.

For the purpose of explaining the invention an example embodying the same has been shown in the accompanying drawing, in which the same letters of reference have been used in all the views to indicate corresponding parts.

In said drawing—Figures 1 to 3, are plan views of the switch showing the same in different positions of its parts, Fig. 1, showing the parts in the positions in which the regulating lever has been set in switching position and the maximum relay is not operated, Fig. 2, showing the same in the positions in which after actuation of the maximum relay the drum has been returned into zero position and the regulating lever is locked against operation by the spring, and Fig. 3 showing the same in the positions in which

the regulating lever has been released and returned into initial position, and in which the spring acting on the switch drum has again been put under tension.

Referring to the example illustrated in the drawing, the switch consists of a drum *a* which is adapted to be operated by a regulating lever *b*. To the drum *a* an arm *c* is secured which carries a pin *d*. The latter is adapted to be engaged by a pawl *f* which is mounted on the regulating lever *b* or an arm *e* connected therewith, and is held in its position by a second pawl *g* which is made integral with an arm *h* adapted to be acted upon by a maximum relay *i*. Between the arms *c* and *e* a spring *k* is interposed which tends to return the drum *a* into initial position. Furthermore the pawl *g* is provided with an arm *l* which is adapted to engage in the teeth of an arc shaped locking member *m* secured to the casing of the switch drum.

In Fig. 1 I have shown the parts in positions which correspond to the ordinary operation and with the regulating lever in the position V. If the maximum current is admitted with the parts of the switch arriving in this position, the maximum relay *i* attracts its core which is thereby thrown against the arm *h* of the pawl *g*, so that the latter releases the locking pawl *f* and the pin *d*. Thereby the switch drum *a* is released and it is rocked by the spring *k* into the position in which the current is switched off. Simultaneously the arm *l* is brought into engagement with one of the teeth of the locking member *m*, so that the regulating lever *b* can not follow the pull of the spring *k* as long as the maximum relay is energized by the current and presses against the pawl *g*. Fig. 2 shows the parts in the positions which they now assume. To throw the pawl and ratchet mechanism into engagement the operator turns the regulating lever into zero position, so that the pawl *f* gets again into engagement with the pin *d*. Thereby also the spring *k* is put under tension for the following operation. Now the parts are in the positions shown in Fig. 3.

I claim herein as my invention:

1. In a switch, the combination with the contact making and breaking member, the regulating member and means intermediate the contact making and breaking member and regulating member tending to retract

105

110

the contact making and breaking member into contact breaking position, of means for rigidly connecting said contact making and breaking member and regulating member, electrically controlled means for throwing said connecting means out of operation, and means operative when disconnecting the regulating member and contact making and breaking member to lock the regulating member in position.

2. In a switch, the combination with the contact making and breaking member, the regulating member and a spring intermediate the contact making and breaking member and regulating member tending to retract the contact making and breaking member into contact breaking position, of a pawl

on the regulating member for rigidly connecting said contact making and breaking member and regulating member, a locking pawl on the regulating member normally holding said connecting pawl in connecting position, a maximum relay adapted to throw the locking pawl out of holding position, and means located in position for engagement by said locking pawl when acted upon by the relay and for locking the locking pawl in position.

In testimony whereof I affix my signature in presence of two witnesses.

MAX VOGELSANG.
